UNITED STATES PATENT OFFICE.

CHARLES L. WAGANDT AND JOHN S. HULL, OF BALTIMORE, MARYLAND.

SOLDERING-TOOL.

SPECIFICATION forming part of Letters Patent No. 379,141, dated March 6, 1888.

Application filed February 16, 1887. Serial No. 227,628. (No model.)

To all whom it may concern:

Be it known that we, CHARLES L. WAGANDT and JOHN S. HULL, both of the city of Baltimore and State of Maryland, have invented 5 certain Improvements in Soldering Tools, of which the following is a specification.

This invention relates to certain improvements in that class of soldering-tools in which the soldering-block is kept constantly in a 10 heated condition by means of a flame applied directly thereto; and it consists in certain details of construction of the said tool, as will hereinafter fully appear.

In the description of the said invention 15 which follows reference is made to the accompanying drawings, forming a part hereof, and in which—

Figure I is a partly-sectional view of the improved soldering-tool, and Fig. II an under 20 side view of a portion of the same. Fig. III is a cross section of Fig. I, taken on the dotted line *x x*. Fig. IV is a top view of Fig. II.

Similar letters of reference indicate similar parts in all the figures.

25 In the said drawings, A is the soldering-block of the tool, which is of the hatchet order—that is to say, the block is provided with a handle which projects in a lateral direction, and its soldering-edge is practically in a line 30 parallel with the handle. This soldering-block is held with its upper edge within a casing, G, by means of a set-screw, *k*, and a gib, *l*, at one end of the casing. The rounded edge of the block A stands a short distance from the crown 35 of the casing, which is denoted by *m*. The inflammable gas is introduced to the space *n* between the crown and the upper edge of the block A through the rigid pipe *o* and the flexible pipe *p*, and the crown and side of the casing are provided with holes *q* to admit air to 40 support combustion.

The handle of the tool consists of a pipe, C, screwed into a socket at the end of the casing, and a wooden sleeve held to the pipe by means of the nut E and a collar, *a*. The tool is intended to be supported independently of the flexible gas-pipe by means of a rod, as shown 45 in Letters Patent No. 371,806, granted to us on the 18th day of October, 1887. The swivel to which the suspensory rod is attached is 50 shown in Fig. I and denoted by *b*. The gas is ignited at the end of the pipe *o* within the space *n*, and the flame follows the surface of the soldering-block, escaping at the under side of the casing, which is open. Spaces *d* are recessed 55 out at the sides of the soldering-block and between the same and the casing for the passage of flame, leaving the inner sides of the said casing with corner-pieces *c*, as shown in Fig. II. Air to support combustion of the gas is 60 introduced to the spaces around the soldering-tool through holes *q* in the crown and sides of the casing, as before stated.

We claim as our invention—

In a soldering-tool, the practically rectangular casing G, having its sides and crown perforated for the admission of air and gas, and corner-pieces, as described, combined with a soldering-block which is inserted in the said casing and fastened between the said corner-pieces, whereby spaces are left between the said soldering-block and the sides of the casing, substantially as and for the purpose specified. 70

CHARLES L. WAGANDT.
JOHN S. HULL.
